UNITED STATES PATENT OFFICE

EMIL G. JURGENS AND HAZEN K. BECKER, OF CHICAGO, ILLINOIS, ASSIGNEES TO
PETERS MACHINERY COMPANY, OF CHICAGO, ILLINOIS, A CORPORATION OF ILLINOIS

CARTON-BLANK SEPARATING AND FEEDING MECHANISM

Application filed June 8, 1928. Serial No. 283,882.

This invention relates to machines for handling paper or cardboard blanks, particularly to means for separating the blanks, one by one, from a stack of blanks in a supply magazine and delivering the same to a conveying means where, as customary in this class machinery, the separated blanks receive lining paper thereon before being delivered to carton folding and filling machines.

10 The purpose of the invention is to provide improvements, in machines of this class, relating particularly to the blank separating means and incidentally to cooperating feeding means for the supply stack of blanks and 15 also to feeding means for separated blanks and lining paper therefor.

The objects of the invention may be accomplished by a construction such as shown in the drawings, wherein:

20 Figure 1 is a longitudinal section of the upper portion of the machine.

Fig. 2 is an enlarged sectional view illustrating the action of the carton blank separating mechanism.

25 Fig. 3 is a side view of the upper portion of the machine.

Fig. 4 is an enlarged detail of a friction means for separating the carton blanks one at a time.

30 Fig. 5 is a fragmentary view illustrating in section a stack of carton blanks and a means for guiding the uppermost blank as it is being separated from the stack.

Fig. 6 is a fragmentary plan view and 35 partly in section, showing the carton blank magazine and the separating mechanism.

Fig. 7 is a fragmentary perspective view illustrating the separating mechanism and feeding means for the carton blank magazine.

40 Fig. 8 is a detail in perspective of a controlling arm for the magazine feed pawl.

Fig. 9 is a front view of the upper part of the machine.

Fig. 10 is a detail in elevation and section 45 of part of the carton blank magazine feed mechanism.

Fig. 11 is a detail in plan and partly in section of the carton blank magazine feed mechanism.

50 The machine illustrated is of the same gen-

eral class as that shown in applicants' patents No. 1,555,957, October 6, 1925, and 1,638,518, August 9, 1927, relating to means for removing one at a time cardboard blanks from a stack of blanks such as blanks cut to the required form for folding into cartons.

55 The present construction is designed to operate upon various grades of cardboard and to separate the same irrespective of the kind of surface treatment thereof, rough, smooth or waxed, and the tendency of the blanks to adhere together at the cut edges. The separating mechanism of the present invention is based upon the idea of causing the separation of one blank from a stack of blanks by 60 frictionally engaging the uppermost blank 65 and causing it to buckle upwardly away from the stack of blanks.

Referring to the drawings, the various parts of the mechanism are driven by rotating shafts 1 to 5 inclusive, extending transversely of the machine and suitably geared together to operate in unison by means of gears or chains.

70 A magazine for carton blanks is provided at the front of the machine by vertical guide members 8 between which is slidably mounted a support 9 for the carton blanks. The support 9 is caused to travel upwardly by a step-by-step motion during the operation of the machine by means of chains 10 (Fig. 9) connected by the fastening screws 11 to a bar 12 upon which the support 9 rests and which is integral with sleeves 13. The sleeves 13 are slidable upon the vertical guide shafts 14. The chains 10 pass over sprocket wheels 15 fast to the transverse shaft 7 which, as shown in Fig. 3, carries a worm wheel 16 meshing with a worm 17 on a vertical shaft 18. The shaft 18 is driven by an oscillating 75 pawl 19 (Fig. 11) which engages a ratchet wheel 20 fast to shaft 18. The pawl 19 is carried by a lever 21 pivoted on shaft 18 and operated by a link connection 22 with a crank 23 on the drive shaft 3. 80

85 The amount of movement imparted to shaft 18 by the pawl 19 for each operation of the pawl, may be regulated by adjustment of curved plate 24 (Figs. 7, 8 and 11). The plate 24 is adjustable around the shaft 18 so 90

as to hold the pawl 19 out of engagement with the ratchet 20 for more or less of the stroke of the pawl. The purpose of this adjustment is to cause the magazine of carton blanks to feed upwardly at a rate corresponding with the thickness of the blanks. In order to make the adjustment of the curved plate 24 automatic to suit the thickness of the carton blanks, the plate 24 is carried by an arm 25 journaled upon shaft 18 and rigid with a pulley 26. A cord 27 passes over the pulley 26, Fig. 7. One end of the cord 27 is attached to a spring 28 anchored to the machine frame. The opposite end of the cord 27 is attached to an arm 29 fast to an oscillating shaft 30. The shaft 30 is oscillated once for each time a carton blank is separated from the remainder of the stack by means hereinafter described. The extent of oscillation of shaft 30 and accordingly the extent of adjustment of the curved plate 24 is determined by a finger 31 carried by an arm 32 fast to shaft 30 and arranged to come into engagement with the top of a stack of carton blanks as shown in Fig. 2. Shaft 30 is rocked in this manner by means of a spring 33 (Fig. 7). The finger 31 is normally held out of engagement with the stack of cartons by an arm 34 fast to shaft 35. The arm 34 engages the shank of a bolt 36 extending laterally from arm 32 which carries the finger 31. When the arm 34 rocks to the right (Fig. 7), the arm 32 follows under the action of spring 33. Spring 28 accordingly draws on the cord 27 which passes around the idler pulley 37 and around the pulley 26 which is rigid with the pawl adjusting plate 24. The oscillation of shaft 35 is effected by a pitman connection 38 between arm 39 fast to shaft 35 and a disc 40 fast to the rotating drive shaft 2.

The carton separating mechanism includes a friction or toothed element 41 carried by a bell crank lever 42 pivotally mounted at the upper end of arm 34. A spring 43 urges the bell crank lever 42 to rock in such direction as to cause friction member 41 to bear downwardly upon the top of the stack of carton blanks which are indicated at 44 (Fig. 1). The action of the friction device 41 on the uppermost blank of the stack of blanks is to cause it to buckle away from the remainder of the stack as indicated in Fig. 2. The separated blank is at this time prevented from sliding off of the stack of blanks by retaining fingers 45 which are rigidly secured to shaft 6. After a blank has been buckled as indicated in Fig. 2, the fingers 45 are rocked away from the edge of the blank and permit the blank to spring back into flattened condition with its edge in cooperative relation with the roller 46 and feed belts 47. The retaining fingers 45 are rocked in this manner by means of a cam 48 fast to drive shaft 4 and cooperating with a roller on the end of an arm 49 fast to shaft 6. The retaining fingers 49 are nor-

mally held in position shown in Fig. 2 by spring 49' (Fig. 3).

It is customary in machines of this class to place a portion of lining paper upon each blank after it is separated from the stack and conveyed out of the machine to the folding mechanism. For this purpose the present machine is provided with a support 50 for a roll of lining paper 51. The lining paper is lead over idling rollers 52 and from there it passes between a feed roller 53 and a pair of frictionally driven pressure rollers 54. The roller 53 is on a constantly driven shaft 55, but the paper is not continuously fed because rollers 54 are arranged to move into and out of feeding relation with the roller 53. The period of time in which contact is made between rollers 54 and 53 determines the length of the strip which is fed for each operation of the blank separating mechanism. The rollers 54 are rocked into engagement with roller 53 by a lever 56 pivoted to shaft 57 and arranged to cooperate with a pair of cams 58, one of which is loose and the other fast on shaft 3. For this purpose the lever 56 carries a roller 59 for cooperating with the cams 58. The length of the crest 60 of the cams 58 may be increased by changing the relative angular positions of the cams as provided for by set screw 61 (Figs. 1 and 9). The set screw 61 passes through a slot 62 in one of the cams and has threaded engagement with the other, so that it may clamp the two together.

A knife 63 for shearing the lining paper cooperates with a fixed blade 64 over which the lining paper passes, and is operated by a cam 65 fast to drive shaft 5. The cam 65 operates on a roller 66 carried by arm 67 fast to shaft 68 to which is also secured the arms 69 carrying the knife 63. After being operated by cam 65 the knife is restored by a spring 70.

When a carton blank is separated from a stack of blanks as shown in Fig. 2, edges of the separated blank which might engage edges on the next lower blank are guided clear of the lower blank by guide fingers 71 (Fig. 5).

The support for the carton blanks may be adjusted upwardly or downwardly independent of the ratchet drive therefor illustrated in Figs. 10 and 11, by means of the hand wheel 72 which is secured to shaft 18.

In the operation of the mechanism described, the main drive shaft 1 is continuously rotated and through gear connections drives the rotating shafts 2, 3, 4 and 5, (Figs. 1 and 3). Shaft 2, by pitman connection 38 (Fig. 7) with the arm 39 on the shaft 35 oscillates the latter shaft and through it effects the reciprocating action of the toothed friction carton separating device 41. This device has a feed motion toward the retaining fingers 45 (Fig. 2) when the latter are in the position shown in this figure. The up-

permost carton blank is thereby buckled as shown in Fig. 2 and at the end of a stroke of the separating element 41 the fingers 45 are rocked upwardly by the action of cam 48. 5 The buckled portion of the carton then straightens out, its edge engaging roller 46 at the point of contact with the belts 47. The separated carton is carried along by belts 47 and as it leaves the machine receives the portion of lining paper severed by the knife 63.

10 The carton blank support 9 is moved upwardly by the worm gearing and pawl and ratchet feed mechanism shown in Figs. 10 and 11 as controlled by the finger 31 (Fig. 2) 15 when in its extreme forward position. This finger moves forwardly under the action of spring 33 (Fig. 7) according to the thickness of the removed carton blank. Through the cord connection 27 with pulley 26 (Fig. 7) 20 the shield 24 is adjusted to regulate the effective stroke of pawl 19.

Although but one specific embodiment of this invention has been herein shown and described, it will be understood that numerous details of the construction shown may be altered or omitted without departing from the spirit of this invention as defined by the following claim.

We claim:

30 In a carton blank separating and feeding mechanism, a supporting frame, a support for a stack of carton blanks, a friction device and a retainer for respectively engaging the surface and the edge of the uppermost blank, 35 means for moving said friction device toward said retainer whereby the engaged blank is moved relative to the next lower blank and separated from the stack by buckling, and guide fingers on said frame located in registering cutout portions of said blanks for 40 guiding the edges of the cutout portions of the engaged blank clear of the edges of the cutout portions of the next lower blank.

Signed at Chicago this 6th day of June, 45 1928.
